UNITED STATES PATENT OFFICE.

JAMES BARCLAY, OF LONDON, ENGLAND.

TYPOGRAPHIC COMPOSING MACHINE.

Application filed October 31, 1924. Serial No. 747,130.

To all whom it may concern:

Be it known that JAMES BARCLAY, subject of the King of Great Britain, residing at 48 Fernwood Avenue, Streatham, London, S. W. 16, England, has invented certain new and useful Improvements in Typographic Composing Machines, of which the following is a specification.

This invention relates to typographic casting and composing machines which employ matrices mounted in a die case or holder, the positions of which matrices relatively to the casting mould are determined by gauges or stops operated from a record strip or pattern, and co-operating with die case positioning mechanism.

The invention refers particularly to casting machines such as are described in the specification of United States Patent 625,998. These machines usually have two series of primary gauges in the form of stops and in each series there is a fixed stop which controls the end row or column of matrices, thus permitting the use of an extra row of matrices beyond the rows decided by the controllable stops. In the usual commercial machine constructed in accordance with the aforesaid specification, 14 controllable stops and a fixed stop in each series, control 15 positions in each direction of movement of the die case or matrix holder.

The present invention consists in improvements the main object of which is to provide for the positioning of an additional row of matrices in the matrix holder in either or both directions of its movement without the necessity of additional movable stops being employed. The capacity of the matrix holder is thereby increased by 15 matrices if applied in one direction only and to 31 if applied in both directions of the movement of the matrix holder.

As regards the application of the invention to a machine such as described in the aforesaid specification a description will first be given of the action of the mechanism affected by the present invention.

The matrix holder on this casting machine as at present constructed carries 225 matrices in 15 rows of 15 matrices per row. A paper ribbon is perforated by a keyboard mechanism for the purpose of controlling the position of the matrix holder upon this "caster" or casting machine. As the matrix holder has 15 movements in each direction a com-

bination of two perforations is used to locate every matrix, excepting when the matrix required happens to be one situated in one of the matrix rows at the two extreme ends of the holder in which case the matrix holder is carried to a zero position or fixed stop, in which cases one perforation only is needed. If the matrix holder is carried to zero in both directions, at right angles to each other, no perforation is needed. The controllable stops or gauges, of which there are fourteen in two series placed at right angles to each other, are in the form of pins elevated when required to act by means of compressed air pressure. The fixed stop for the 15th position consists of a similar pin held permanently upward, so that should the positioning member not meet any obstruction such as an elevated pin, it will be arrested by the fixed pin.

One of the objects of the present invention is to cause the fixed pins to recede or drop to the common level of the other pins, so that they cease to function in the normal manner and allow the matrix holder to be carried a definite move beyond the normal fixed pins, thus permitting of the utilization of further rows of matrices beyond those at present controlled by the perforated paper ribbon and the two fixed stops.

The principal means in bringing this about consists in employing the compressed air (or other controlling agent employed) for controlling the fixed stops referred to. This is achieved by connecting the air pipes leading to two selected movable stops first to an air-deviating mechanism, so that when the air is caused to enter these two selected pipes simultaneously, the paper ribbon being perforated to allow this, the normally zero or fixed stop will be caused to recede or drop, as previously referred to, but when compressed air enters either of the two selected pipes individually or alone, in obedience to the perforations on the paper ribbon, the stops function in the normal manner.

Suitable ducts or piping, valves and vents would be associated with the improved machine for the conduct of compressed air from a convenient source, and for its distribution and exhaust.

Referring to the accompanying drawings:

Fig. 1 is a diagrammatic view showing the invention as applied to an existing typographic casting and composing machine and

contrived to position an additional row of matrices in each of the two directions of movement of the die case.

Fig. 2 is a sectional elevation of the air diverting mechanism according to the present invention and as applied to the arrangement illustrated in Fig. 1 and

Fig. 3 is a diagrammatic view of another embodiment of the invention as contrived for positioning two additional rows of matrices in one direction only of the die case movements.

The die case positioning mechanism including the two series of primary gauges to which the present invention is particularly applicable is that of the machine described in the specification of United States Letters Patent 625,998 already referred to. It is not considered necessary to refer in detail to the positioning mechanism as reference may be had to the above-mentioned specification for a full and detailed description. It is deemed sufficient to indicate the parts cooperating with the mechanism of the present invention. A is the air tower having a series of air ports which are uncovered in predetermined combinations by the perforations in the record strip to allow air to pass to the pistons of the pins or primary gauges. B is one of the series of gauges and for convenience will be referred to as the front pin block, C is the second series of gauges and will be referred to as the rear pin block and D D¹ are the air diverting devices.

The arrangement of air ducts or conduits between the ports of the air tower A and the pistons of both series of gauges B and C generally remain the same as in the commercial machine and these conduits are indicated in Fig. 1 by full lines B^x and C^x.

Certain conduits however instead of leading from the air tower A, in accordance with the present invention, are diverted or do not now lead direct to the gauge pistons but pass through the air diverting device D or D¹ and these conduits are indicated by broken lines.

In the embodiment illustrated in Fig. 1 provision is made for positioning an additional row of matrices in each direction of movement of the die case and two diverters D, D¹ are employed. These two diverters are similar in construction, so that a description of the construction of one of them will serve for both.

Referring to Fig. 2 of the accompanying drawings the air diverting apparatus comprises a block having three valve chambers in which are situated three valves D² D³ D⁴. These valves are coupled respectively with three other valves D⁵ D⁶ D⁷ situated in valve chambers in line with the chambers of the first mentioned valves. Air from a constant supply enters the chambers of the

valve D⁷ by a conduit d and inlet opening d¹. The conduit d² leading from the port B¹³ of the air tower A is led into the chamber of the valve D⁵ above that valve, and the conduit d³ from the port B¹⁴ in the air tower A is led into the chamber of the valve D⁶ above that valve.

When the valves D⁵ D⁶ D⁷ are in the position shown in Fig. 2 the air entering the chamber of valve D⁵ passes out of the chamber by a conduit d² situated above the valve and leading to gauge pin B¹³, similarly air entering the chamber of valve D⁶ passes by a conduit d³ leading out of the valve chamber above the valve to gauge pin B¹⁴. In these positions of the valves D⁵ and D⁶ the air from the tower A to the pins B¹³ and B¹⁴ operates as hitherto. The constant air entering the valve chamber D⁷ passes by a conduit d⁴ above the valve to the piston of air pin B¹⁵. This pin instead of being a fixed pin as hitherto is movable and is held projected by the constant air.

The components of the signal for operating the diverter, if used along or in conjunction with the components of other character signals, do not operate the diverter, which is only operated when these two components are presented together at the air tower simultaneously with a character or symbol signal.

A portion of the air entering from the conduit d³ into the chambers of valve D⁶ passes by a conduit d⁶ (see Fig. 2) to the lower end of a chamber in which is situated a piston valve D⁸. This valve in rising lifts from its seat a spring controlled valve D⁹ to the chamber of which air is admitted by a conduit d⁷ which is in communication with the chamber of valve D⁶. When, in the working of the mechanism, air is admitted beneath the valve D⁸ or above the valve D⁹ the diverter is inoperative. When, however, air enters the chambers of the valves D⁸ and D⁹ simultaneously, these two valves are operated and air from the chamber of the valve D⁹ passes through the now open valve D⁹ and by conduit d⁸ to beneath the piston valves D² D³ D⁴. These pistons are of larger diameter than the piston valves D⁵ D⁶ and D⁷ and therefore the valves D² D³ and D⁴ are operated against the pressure in the chambers of the valves D⁵ D⁶ D⁷. When the piston valves D⁵ D⁶ and D⁷ are raised the constant air is cut off by the valve d⁵ from the pin B¹³ which is thus withdrawn or allowed to drop, allowing the primary positioning mechanism or positioning jaws to engage pin B¹⁶ which is the additional and stationary pin in accordance with this invention.

The arrangement of the diverter D¹ between the conduits C¹ to C¹⁴ of the air tower and the pins of the gauging devices C is similar to that above described with reference

to the diverter D and the gauging device B and need not be described in detail. It provides for a second additional row of matrices in the other direction of movement of the die case.

When it is required to provide for only one additional row of matrices one diverter only will be employed. It is also contemplated by the present invention to provide for the positioning of two or more additional rows of matrices in one direction only of the movements of the die case.

An embodiment of the invention so applied is illustrated in Fig. 3 of the accompanying drawings. In this embodiment of the invention the two additional rows of matrices are arranged in the die case in the direction which is controlled by the gauging device C. In addition to making the fifteenth pin a movable one two additional pins C¹⁶ and C¹⁷ are provided, of which the pin C¹⁷ is a movable one and the pin C¹⁶ is a fixed one.

The diverter D in this embodiment is furnished with four valves D¹⁰ D¹¹ D¹² and D¹³, which are in the form of hollow pistons closed at their lower ends. Air from a constant supply enters a chamber controlled by a portion of the valve D¹³ through a conduit d¹⁰ and when the valve is in its normal position as shown in Fig. 3 this air passes round a reduced portion of the valve D¹³ and thence by an outlet conduit d¹¹ to the pin C¹⁵ of the gauging devices C, this pin now being a movable one, but retained in its elevated position by this constant air from the port C¹² in the tower A passes by a conduit d¹² to a chamber controlled by a portion of the valve D¹⁰ and when the valve is in its normal position the air passes around a reduced portion of the valve and by a conduit d¹³ to the piston of gauge pin C¹².

Air from the port C¹³ in the air tower A passes by a conduit d¹⁴ to a chamber controlled by a portion of the valve D¹¹ and when the valve is in normal position (see Fig. 3) passes around a reduced portion of the valve and by a conduit d¹⁵ to the pin C¹⁵ of gauging device C. The conduit d¹⁴ is branched before it reaches the valve D¹¹ and these branch conduits d¹⁵ and d¹⁶ lead respectively to the lower ends of the chambers for valves D¹⁰ and D¹² in such a manner as to raise these valves. Air from the port C¹⁴ passes by a conduit d¹⁷ to a chamber controlled by valve D¹² and in the normal position of this valve passes round a reduced portion thereof and by a conduit d¹⁸ to gauge pin C¹⁴. The conduit d¹⁷ is branched before it reaches the valve D¹² the branch d¹⁹ thereof entering a chamber beneath the valve D¹¹ causing it to rise.

The above is the ordinary action when the pins C¹², C¹³ and C¹⁴ are responding to normal signals.

From above the valve D¹⁰ a conduit d²⁰ leads to one of the additional pins C¹⁷ which is a movable one. The pin C¹⁷ is projected when a character signal is presented at the air tower in company with a special signal, the components of which uncover the ports C¹² and C¹³. When such a signal is presented the valves D¹⁰ and D¹² are raised. The air from port C¹³ raises valves D¹⁰ and D¹³ and this cuts off the air from conduit d¹³ thus allowing gauge pin C¹² to fall, a vent being opened through the valve D¹⁰. The air around valve D¹⁰ now passes through conduit d²⁰ to pin C¹⁷. One of the positioning jaws cooperating with the gauge pins is engaged by the raised pin C¹⁷ and the other jaw passes over the pin C¹³ and comes against the jaw engaged by pin C¹⁷.

The pin C¹⁵ is held in projected position by the constant air through conduit d¹¹. When the second additional and fixed pin C¹⁶ is to be used the air must be cut off from this conduit. To bring this about a special signal accompanying a character signal is employed. This signal comprises components uncovering ports C¹³ and C¹⁴ in the air tower. The air from port C¹³ raises the valves D¹⁰ and D¹² and the air from port C¹⁴ raises the valve D¹¹.

No action results from the rising of the valve D¹⁰ as there is no air now present in the conduit d¹².

The valve D¹¹ by rising cuts off the air from conduit d¹⁵ causing the gauge pin C¹⁵ to be withdrawn the air being vented through an opening in the valve D¹¹.

The valve D¹² by rising cuts off the air from conduit d¹⁶ causing the gauge pin C¹⁴ to fall, the air being vented through a hole in the valve D¹². Also when the valve D¹² is raised the air in conduit d¹⁷ is led around the upper reduced part of valve D¹² by a conduit d²¹ to beneath the valve D¹³ raising this latter valve. When the valve D¹³ is raised air is cut off from conduit d¹¹ thus allowing pin C¹⁵ to be withdrawn, the air being vented through a hole in the valve D¹³. The positioning jaws therefore meet on the fixed pin C¹⁶.

What I claim is:—

1. In a typographic casting machine the combination with a positioning mechanism comprising a series of signal-controlled gauges, of an additional gauge, and a diverter responsive to a special signal to operate the additional gauge.

2. In a typographic casting machine the combination with a positioning mechanism comprising a series of signal-controlled gauges, and a normally fixed gauge, of an additional gauge and a diverter responsive to a special signal to effect the withdrawal of the normally fixed gauge.

3. In a typographic casting machine the combination with a positioning mechanism

comprising a series of signal-controlled gauges, of an additional gauge and a valve mechanism responsive to a special signal to divert the motive power from one or other of the normal gauges to the additional gauge.

4. In a record strip-controlled typographic casting machine the combination with a series of normal gauges operated by designating signals in the record strip 10 of a plurality of additional gauges, and a valve mechanism responsive to special signals in the record strip to operate one or other of the additional gauges.

5. In a record-strip controlled typographic casting machine, the combination with a positioning mechanism comprising a series of gauges responsive to designating signals in the record strip and a normally fixed gauge, of an additional gauge and a valve

mechanism responsive to special signals in 20 the record-strip to withdraw the normally fixed gauge or operate the additional gauge.

6. In a record-strip controlled typographic casting machine the combination with a positioning mechanism comprising a 25 series of gauges responsive to designating signals in the record strip and a normally fixed gauge, of a plurality of additional gauges, and a diverter comprising a plurality of valves responsive to special signals 30 in the record strip, to operate one or other of the additional gauges.

In testimony whereof he affixes his signature in presence of two witnesses.

JAMES BARCLAY.
